UNITED STATES PATENT OFFICE.

DAVID J. CARTWRIGHT, OF BOSTON, MASSACHUSETTS.

ORDNANCE.

1,137,953.

Specification of Letters Patent.

Patented May 4, 1915.

Application filed February 23, 1907. Serial No. 358,813.

To all whom it may concern:

Be it known that I, DAVID J. CARTWRIGHT, citizen of the United States, residing at Boston, county of Suffolk, and State of Massachusetts, have invented a certain new and useful Improvement in Ordnance, of which the following is a specification, reference being had therein to the accompanying drawings.

10 The angle of elevation of a mounted gun with reference to the plane of the supporting platform of the gun carriage for any given range is usually determined on the basis that the platform is in a fixed position or at a given angle. Therefore if the platform shifts from this given angle, it will derange the elevation of the gun and it will then be necessary to either change the angle of the gun with relation to the platform or 15 wait until the platform is returned to its given angle before firing the gun. Heretofore, so far as known to me, there has been no mechanism by which the given elevation of the gun can be maintained while this 20 platform shifts.

When vessels are in action, especially when there is a heavy sea, the rolling and pitching of the vessel constantly changes the angle of the gun platform relative to a horizontal plane so that it is impossible by hand 25 operated mechanism to elevate or depress the gun quickly enough to be practicable. Therefore in practice the gunner is often obliged to wait a long time until the ship 30 temporarily assumes a stationary position at the top of the roll before firing.

My invention relates especially to mechanism for controlling the elevation or training of a gun, and while it is particularly designed for application to a gun on ship board, it is not limited to such use.

One object of my invention is the production of a device which when applied to a gun and its mount will maintain the gun at 45 a given angle of elevation relative to a horizontal plane independent of the movement of the platform upon which it may be placed; a second object is the production of a means of quickly changing the angle of 50 elevation or depression and maintaining the gun at said new angle.

My invention also has for its object certain means of controlling a movable support for a self leveling member, and certain

mechanism for opening and closing an electric circuit.

My invention also has for its object to relieve the gun pointer of the manual labor of operating the directing mechanism, thereby enabling him to keep his body steady, 60 also to keep his eye steady on the line of sight and avoids frequent changing of gun pointers.

There is also a saving of time in loading. When the ship is rolling heavily during the 65 loading of the gun, in the operation of the gun as the gun is ordinarily constructed, much time is lost by the moving of the gun relative to the deck. With my device attached to a gun, when the switch which connects the electric circuit through the automatic part is opened, the gun partakes of 70 all the movements of the ship, and when the gun is loaded and the circuit through the automatic part is closed by means of the 75 switch, the elevating gear will thereby be actuated to immediately move the gun to its proper elevation independent of the direction of the roll.

Another object of the invention is to automatically operate the directing mechanism of a gun carriage to move the gun and its associated parts in opposite direction to the roll of the ship.

My invention will now be fully described 85 and particularly pointed out in the claims at the end of the specification.

In the drawings,—Figure 1 is a side view of the left side of a gun and its mount having attached thereto the motive power and 90 operating mechanism. Fig. 2 is an enlarged view of the operating mechanism and electromagnets, detached from the gun. Fig. 3 is a side view in elevation of the operating mechanism detached from the gun, the magnets being removed. Fig. 4 is an enlarged detail side view of the adjustable contact plate with contacts and insulating plate which may be placed on either side of the gun. Fig. 5 is a sectional view on line 5—5 100 of Fig. 4, the pivoted rod being broken off. Fig. 6 is a diagram illustrating the electrical circuits.

Referring to the drawings,—The gun 1 is mounted in the usual manner in the sleeve 105 2 which is supported by trunnions 13 in the top carriage 5 on pedestal mount 6. The yoke 3 and recoil cylinder 12 are all of well

known form. The toothed elevating arc 4 secured to the gun sleeve 2 is operated through a pinion and worm wheel by the elevating worm screw 9 mounted on shaft 8 which has its bearings in the top carriage 5. A hand wheel 7 is mounted on a shaft 71 having a pinion 72 engaging with a bevel gear 73 on shaft 8 by which the elevating screw can be operated to elevate or depress 10 the gun. 10 is a training wheel. All of the above elements are well known and represent one form of construction to which my invention may be applied.

Mounted on the elevating screw shaft 8 15 is a bevel gear 14 which meshes with bevel gear 15 mounted on the rotating shaft 16. The shaft 16 is connected with operating mechanism which will be hereinafter described by which the shaft 16 is rotated 20 either to the right or left as occasion requires, thereby turning the elevating screw 9 to either elevate or depress the breech of the gun if the gun platform is stationary, or to maintain the gun at a fixed elevation if 25 the gun platform is moving. When the wheel 7 is turned by hand, the gear 14 is also turned, and the gun is elevated or depressed, and when the gear 14 is operated by the motor, the gun is elevated or depressed. 30 Gears 17 and 20, which I term respectively the breech depressing gear wheel and the breech elevating gear wheel, are mounted loosely on shaft 16 and are driven in opposite directions to each other by any well 35 known means. The mechanism which I have shown for that purpose and the best now known to me is the following: a main driving gear 21 driven by an electric motor 26 meshes with the gear wheel 20. Gear 40 wheel 21 also meshes with gear wheel 17. On shaft 16 is also fixed a gear wheel 15 which meshes with gear wheel 14.

There are other well known ways by 45 which the shaft 16 may be driven in opposite directions, the particular means by which it is done not being essential, whether by gearing, belting or otherwise. Splined on the shaft 16 between the two gears 17 and 20 is a cone clutch 37, 38 which can slide 50 lengthwise on the shaft. The sliding movement of the cone is given by a shipper bar 22.

When the shipper bar 22 is moved to the right, it will cause the clutch 37 to engage 55 with the gear 17 and rotate the shaft 16 in a direction to depress the breech of the gun. When the shipper bar 22 is moved to the left it will cause the clutch 38 to engage with gear 20 and rotate the shaft 16 in a 60 direction to elevate the breech of the gun. In the drawings, both clutches are shown disengaged. The shipper bar 22 is actuated by either the electromagnet 24 or 25 according to whichever of the two magnets is energized. When the armature is equi-dis-

tant between the magnets, the friction cone is disengaged from the clutches. The shipper may also be moved by hand lever 23 through connecting rod 11.

In Fig. 1 hand operated means are shown 70 by lever 23, also lever 18^a on rheostat 18 and handle 19^a on rheostat 19. The hand lever 23 is for the purpose of changing the direction of motion by throwing the clutch 37, 38, into engagement with gear wheels 17 and 75 20 through the connecting rod 11, see Fig. 2. In the construction of the clutch, a leather and metal surface are brought together. By varying the pressure on the hand lever 23 one can cause more or less slip at the clutch 80 which will change the speed of the operating mechanism. If any greater change is required the change of speed may be accomplished by operating the lever 18^a on the rheostat 18 or handle 19^a on rheostat 19 to 85 produce a change of speed in the motor itself.

The means whereby the change of direction and also change in speed is effected is shown in Fig. 2 through the connecting rod 11 90 and shipper bar 22 acting upon the friction clutch 38, 37. When the device is used automatically a slight variation in speed may be produced by operating the hand lever 23 to reduce the friction caused by the magnets 24, 25, which throws the lever 22 into engagement with one or the other of the friction cone wheels, causing a slip between the clutched surfaces.

18 is the ordinary type of rheostat connected in series with the armature of an electric motor in the usual manner. The rheostat 19 is of the usual type connected in series with the fields of the electric motor, and may be operated by hand to produce the same result as the rheostat 18, that is, to change the speed of the motor. The hand operated means shown in the drawings are 23, 19^a and 18^a. 23 is used to change direction as well as to vary the speed by 100 varying the pressure. The purpose of the rheostat 19 in addition to the rheostat 18 is to give the close speed regulation necessary to keep on the target. Rheostat 18 is for the coarse regulation and rheostat 19 115 is for the close regulation.

Secured to the rotatable member or face of the trunnion 13 is an extension 27. Pivoted on the journal 39 projecting from the trunnion extension is an adjustable member 120 28 which I term the adjustable contact plate carrying the contact points 48 and 53. This plate will move with the trunnion or its support and also may be adjusted on its pivot by the angle adjusting screw 42.

On the trunnion extension 27 is located a plate 40. Pivoted to the upper end of plate 40 is a left hand threaded block 41 and pivoted to the upper end of plate 28 is a 125 right hand threaded block 43.

The adjusting screw 42 passes through blocks 41 and 43 and is formed with right and left hand screw-threads so that by turning the wheel 31 the plate 28 is turned on its 5 pivot toward or from the upper end of plate 40 for the purpose of changing the angle of the electric contacts 48 and 53 located on plate 28 relative to the longitudinal axis of the gun, plate 40 being fixed with relation to the trunnion while plate 28 turns. This combination of plate 40 and 28 together with their operating parts I term the angle adjuster. Attached to the block 43 is a graduated scale 34 to obtain the proper 10 elevation for any particular range.

When the shaft 8 rotates, it will revolve the elevating screw 9, thereby elevating or depressing the breech of the gun 1 and arc 4, and rotating the trunnion 13. The rotation of the trunnion 13 carries with it the adjustable contact plate 28 and the angle adjuster heretofore described. The adjustable contact plate 28 and its associated parts mounted on the rotatable member or trunnion will be unchanged in their relation to each other by the rotation of the trunnion.

Pivoted on the reduced extension of journal 39 is a self leveling member which in the drawings is shown in the form of a rod 29. Attached to the self leveling member is a contact pin 30 which preferably is insulated from the rod 29 as shown by insulating material 35. Attached to the gun carriage are two contact plates 32 and 55 insulated from each other and from the gun carriage by insulating plate 36. From the top of the trunnion extension 27 is an arm 54 which supports and carries two contact pins 33 and 57 which are insulated therefrom and from each other. Pin 33 is in electrical connection at all times with contact point 53 through wire 44, and pin 57 is in electrical contact with contact point 48 through wire 45. Contact plates 32 and 55 are adjustable so that the arc of automatic control or the movement of the gun within its carriage may be regulated.

Coil 24 is made an electromagnet when an electrical connection is established between contact pin 30 and contact point 53. Coil 25 is made an electromagnet when electrical connection is established between contact pin 30 and the other contact point 48. In the drawings, the pin 30 is shown in such position that an electrical connection is not established with either of the coils and neither of them is energized. But a very slight movement of the adjustable plate 28 will bring the pin 30 into contact with one or the other of the contact points 48 and 53. When the contact is with point 53 and coil 24 is energized, the circuit is through wire 46, coil 24, wire 47, bind-screw 56, contact plate 32, pin 33, wire 44, contact point 53, pin 30, wire 49 and switch 50. When

the contact is with point 48 and coil 25 is energized, the circuit is through wire 51, coil 25, wire 52, binding screw 58, contact plate 55, pin 57, wire 45, contact point 48, pin 30, wire 49 and switch 50.

When the gun 1 is adjusted to any angle relative to a horizontal plane, the rod 29 swings plumb end free between the contact points 48 and 53, and the adjustable plate 28 hangs plumb so that the contact point 30 rests between contacts 48 and 53. Any change in the angle of the platform upon which the support for the leveler is placed will bring contact point 30 into contact with one or the other of the contacts 48 and 53, thus energizing one of the coils 24 or 25. The magnet thus energized will attract shipper bar 22 which will move the cone clutch 37, 38, into engagement with its gear 17 or 20, causing shaft 16 and elevating screw 9 to rotate in the manner previously described.

If the movement of the platform is in a direction tending to elevate the breech of the gun, the circuit will be made so as to energize the coil which causes shaft 16 to rotate in a direction to depress the breech of the gun. If the movement of the platform is in a direction tending to depress the breech of the gun, the circuit will be made through the coil which causes the shaft 16 to rotate in the direction to elevate the breech of the gun.

When the platform is tipped at a greater angle than it is possible for the gun to move within its carriage or gun port, a means is provided for automatically disconnecting temporarily one or the other of the circuits leading to the electromagnets 24, 25. Any further movement of the platform in the same direction will break electrical connection between one or the other of the adjustable contact plates 32 and 55 which are attached to the side of the gun carriage and one or the other of contact points 33 and 57 attached to the gun by reason of said contact points 33 and 57 having slipped off of contact plates 32 and 55, thus rendering the directing mechanism inert until such time as the movable platform moves back and brings contact point 30 into contact with that one of the insulated contacts 48, 53, with which it was not last in contact, and thus actuating the elevating and depressing mechanism in the reverse direction.

Located convenient for the gun pointer 120 is a switch 50 which breaks the main circuit in wire 49 to cut in and cut out the automatic controlling mechanism. There is also located convenient for the gun pointer two rheostats 18 and 19 for controlling the speed of the motor. Rheostat 18 is in series with the armature and rheostat 19 is in series with the field.

The adjustable plate 28 and rod 29 and angle adjuster are shown as attached to the

end of a trunnion on the side of the gun. I do not, however, limit myself to the attachment of my device to that particular part of the gun, so long as it is attached to any part of the gun which is rotated or to a support which is rotated when the gun is elevated or depressed.

If from any cause the automatic controlling mechanism becomes deranged, the gun 10 may be pointed by wheels 7 and 10 in the usual manner. Instead of a pivoted rod, a pendulum or any well known self leveling device to which are attached electrical contacts may be employed by which electrical 15 contact is made with adjustable electrical contacts carried by the gun to control the operating mechanism, and come within the scope of my invention.

While the invention has been particularly 20 described as employed in controlling the elevation or training of a gun, it is obvious that it may be employed for other purposes and, therefore, it is not intended that the claims shall be limited to use in connection 25 with a gun, but that they shall also cover the uses of the invention wherever applicable to any apparatus mounted on a movable platform.

What I claim is:

30 1. In combination with a gun supported on the deck of a vessel, a self leveling member, a plurality of electrical contacts mounted on the gun and insulated therefrom and from each other, an electrical contact carried by the self leveling member which when the vessel rolls will make contact with one of said gun contacts, directing mechanism connected with the gun, a rotary shaft connected with the directing mechanism by 35 which when the shaft is rotated the breech of the gun will be elevated or depressed, mechanism connected with the said rotary shaft which can be so controlled as to rotate the shaft in either direction or not at all, 40 electromagnets electrically connected with the electrical contacts on the gun and which are energized only when the contact on the self leveling member connects with one of the gun contacts, and which when energized 45 connect the shaft moving mechanism with the shaft.

50 2. In combination with a gun supported by trunnions, mechanism for elevating and depressing the breech of the gun, a plurality of insulated electrical contacts carried by one of the trunnions, a self leveling member suspended from the trunnion, an electrical contact carried by said self leveling member which, when the gun platform 55 changes its plane in a manner to elevate the breech of the gun, will connect with one of said trunnion contacts and make electrical connection which will actuate the breech depressing mechanism, and which when the 60 gun platform changes its plane in a manner

to depress the breech of the gun will connect with the other trunnion contact and make electrical connection which will actuate the breech elevating mechanism.

3. In combination with a gun supported 70 by trunnions, an adjustable plate pivoted on a support which normally rotates with the trunnion, a plurality of insulated contacts on said adjustable plate, mechanism for elevating and depressing the breech of 75 the gun which is electrically actuated to elevate the breech of the gun when a circuit is made through one of the contacts on said adjustable plate and to depress the breech of the gun when the circuit is made through 80 the other contact on the adjustable plate, a contact piece which makes the connection with one or the other of the contacts on said adjustable plate when the breech of the gun is elevated or depressed, and mechanism by 85 which said adjustable plate may be turned on its pivot and maintained at any given position relative to the trunnion.

4. In combination with a gun, a pivoted 90 plate which moves with the gun, two insulated contacts on said plate, a self leveling member carrying a contact piece, adjusting mechanism for setting the gun to any desired range and which when moved to change the elevation of the gun will cause 95 electrical connection between the contact on the self leveling member and one or the other of the contacts on said plate, and mechanism which is electrically actuated by the connection between the contact on the self leveling member and one of the adjustable contacts to depress the breech relative to the gun platform when the gun platform moves in a direction to elevate the breech, and which is actuated by the connection between the contact on the self leveling member and the other adjustable contact to elevate the breech relative to the platform when the platform is moved in a direction to 100 depress the breech.

5. In combination with a gun, mechanism 105 for changing the angle of the gun, a pivoted plate, mechanism by which said plate may be turned on its pivot and maintained in its adjusted position relative to its support, two electrical contacts on said plate, and a self leveling member carrying a contact piece which connects with one or the other of said 110 adjustable contacts whenever the breech of the gun is elevated or depressed, two electrical circuits in each of which is included one of said adjustable contacts, and an electromagnet in each of said circuits, which, when energized, will cause the mechanism for changing the angle of the gun to become 115 operative.

6. In combination with a rotary member, mechanism for changing the angle of said rotary member, a plate pivoted on said rotary member, insulated electrical contacts 120

- carried on said plate, mechanism by which the said plate may be turned on its pivot and held in its adjusted position relative to said rotary member, a self leveling member pivoted on the pivot of said plate and an electrical contact carried by said self leveling member which will be connected with one or the other of the contacts on said plate whenever the plate is rotated in either direction, and electrical circuits which are opened and closed by the movement of said contacts, which, when closed, will cause the mechanism for changing the angle of said rotary member to become operative.
7. In combination with a vessel, a self leveling member suspended from a rotatable support whose center may remain constant in its position relative to the deck of the vessel, a reversible clutch mechanism, and electromagnets which actuate said clutch mechanism through the self leveling member when said support is moved relatively to the self leveling member in one direction due to the movement of the vessel, so as to cause said clutch mechanism to rotate the support in the reverse direction.
8. In combination with a gun mounted on a movable support, adjustable electric contacts which move with the gun, means for adjusting said contacts, a self leveling member carrying a contact piece, adjusting mechanism for setting the gun to any desired range, and which when moved by hand to change the elevation of the gun will cause electrical connection between the contact on the self leveling member and one or the other of the contacts on said plate, and reverse clutch mechanism which is electrically actuated by the connection between the contact on the self leveling member and one of the adjustable contacts to elevate or depress the breech of the gun to the desired angle of elevation or depression, and means which when the support for the self leveling member has moved through an arc equal to the arc of the elevating and depressing mechanism will cause the elevating and depressing mechanism of the gun mount to become inert until the reverse contact shall be made again by the reverse movement of the movable support.
9. In combination with a gun mounted on a movable support, mechanism by which the gun may be set to the proper elevation for a given range, mechanism which when the support is moved so as to elevate or depress the breech of the gun, will actuate the directing mechanism to counteract the elevation or depression of the breech of the gun occasioned by the movement of the support, and adjustable means whereby when such movement exceeds the range of counteraction of the elevating and depressing mechanism will render said elevating and depressing mechanism inert until the return move-
- ment brings the gun back within the arc of the automatic control.
10. In combination with a gun mounted on the deck of a vessel, directing gear for the gun, a self-leveling member, mechanism which when the platform is moved in a direction tending to either elevate or depress the breech will counteract that tendency, said counteracting mechanism being controlled by electric contacts attached to said self-leveling member which when the gun platform moves makes electrical connection to set in operation the counteracting mechanism.
11. In a gun mount, a self-leveling member, a motor and means operated thereby controlled by said self-leveling member for controlling the direction of transmission from the motor to the directing mechanism to automatically maintain the gun at any given angle of elevation.
12. In a gun mount, a self-leveling member, a motor for operating the elevating gear and means operated thereby controlled by said self-leveling member for controlling the direction of transmission from the motor to the directing mechanism to maintain the gun at any given angle of elevation.
13. In a gun mount, electrical contacts carried by the gun, a self leveling member, which is operated in the direction of the longitudinal axis of the gun, carrying an electrical contact, a motor and separate means operated thereby and controlled by said contacts for elevating or depressing the gun independent of the direction of rotation of the motor.
14. In a gun mount, electrical contacts carried by the gun, a self-leveling member carrying an electrical contact, a motor and means operated thereby controlled by said contacts for controlling the direction of transmission from the motor to the directing mechanism for automatically maintaining any given angle of elevation of the gun.
15. In a gun mount, a self-leveling member carrying electrical contacts, an adjustable member carrying electrical contacts attached to the gun, a motor and means operated thereby controlled by said electrical contacts for controlling the direction of transmission from the motor to the directing mechanism to automatically maintain the gun at any given angle of elevation.
16. In a gun mount, a self leveling member carrying electrical contacts, an adjustable member carrying electrical contacts and attached to the gun, hand operated means for changing the angle of the contacts relative to the gun, a motor and a reversible clutch controlled by said electrical contacts to change the angle of elevation of the gun independent of the direction of rotation of the motor.
17. In combination with a gun mounted

- 6
- on a gun mount, directing gear for the gun, mechanism which when the deck mount is moved relative to a horizontal in a direction tending to change the direction of the gun is adapted to actuate said directing gear to counteract that tendency, a motor, and hand operated means for controlling the speed of the motor and direction of motion of said directing mechanism.
18. In combination with a gun or apparatus mounted on a movable platform, a prime mover or motor rotating continuously in the same direction, a directing mechanism mounted on the support for the gun or apparatus and partaking of all the movements of the support, a reversing friction clutch electrical contacts carried by the gun or apparatus whereby said directing mechanism is actuated through said friction clutch to move the gun in opposition to the movement of the platform upon which the gun or apparatus and its support are placed, and means for varying the speed of movement of the directing mechanism.
19. In combination with a gun mounted on a deck mount, directing mechanism for the gun, a reversing clutch, and mechanism carried by the gun mount which is controlled by the movement of the deck mount to actuate the directing mechanism and counteract the tendency of the gun to move with the deck mount.
20. In combination with a gun, directing gear for the gun, a motor fixed with relation to the gun mount for actuating said directing gear, and means for controlling the direction and means for controlling the speed of said directing gear independent of the speed or direction of rotation of said motor.
21. In combination with a gun mounted on a deck platform, a self-leveling member, directing gear for the gun, mechanism which when the deck platform is moved in a direction tending to either elevate or depress the breech will counteract that tendency, the counteracting mechanism being controlled by electrical contacts attached to the gun and self-leveling member, whereby when the platform moves in either direction an electric circuit is closed to set in operation the counteracting mechanism.
22. The combination of an ordnance member to be trained, a prime mover for transmitting movement to said member, a source of energy for said prime mover, an inertia held member comprising means for controlling the direction of movement of the ordnance member, and means controllable at will for varying the supply of energy to said prime mover.
23. The combination of an ordnance member to be trained, an electric motor for shifting the position thereof, a source of electricity for said motor, an inertia held member, electrical means controlled thereby for controlling the direction of movement of said member, a rheostat for varying the current supplied to the motor and a second rheostat for further varying the supply of said current.
24. The combination of a gun to be trained, means for moving said gun, means controllable by undesirable movement of the gun support for automatically controlling the direction of movement transmitted to the gun, and means controllable by hand for varying the effect of the moving means to regulate the speed thereof.
25. The combination of an ordnance member to be trained upon shipboard, means for shifting said member simultaneously with the occurrence of undesirable movements of the vessel, means for reversing the movement of said member concomitantly with the reversal of the direction of movement of the vessel, and means for thereafter causing said member to move at a speed which will be compensatory to the speed of movement of said vessel, whereby said member will tend to remain in trained position despite undesirable movements.
26. In combination with a gun mounted on a movable platform, a prime mover or motor rotating continuously in the same direction, a directing mechanism mounted on the support for the gun, and partaking of all the movements of said support, electrical contacts carried by the gun, a reversing friction clutch which in combination with said electrical contacts actuates the said directing mechanism to move the gun relative to its support in opposition to the movement of the platform upon which the gun and its support are placed, means whereby said reversing friction clutch may be operated both electrically and by hand, and means for varying the speed of movement of the directing mechanism.

In testimony whereof I affix my signature in presence of two witnesses.

DAVID J. CARTWRIGHT.
